(57) **CLAIM**

The ornamental design for a volt-ohm-ammeter, as shown
and described.

DESCRIPTION

FIG. 1 is a top and left front perspective view of a volt-ohm-ammeter, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a left side elevational view thereof, with a clamp
sensor detached by way of reference only;

FIG. 9 is a rear elevational view thereof, with test rods
detached by way of reference only;

FIG. 10 is a front elevational view thereof, with the clamp
sensor and test rods detached by way of reference only.

FIG. 11 is a bottom plan view thereof, with the clamp sensor
and test rods detached by way of reference only; and,

FIG. 12 is a top and left front perspective view thereof,
with the clamp sensor and test rods detached and with cords
loosened by way of reference only.
